(57) **CLAIM**

The ornamental design for a pince-nez, as shown and described.

DESCRIPTION

1.1 is a front elevational view of pince-nez showing our new design;

1.2 is a top, front and left side perspective view thereof;

1.3 is a top, front and right side perspective view thereof;

1.4 is a right side elevational view thereof, the left elevational view being the same;

1.5 is a top plan view thereof, the bottom plan view being the same;

1.6 is a rear elevational view thereof.

1 Claim, 6 Drawing Sheets
